UNITED STATES PATENT OFFICE

1,980,773

LIGHTING UNIT

Davis H. Tuck, Norwalk, Conn., and Wilson Rosebraugh, Newark, Ohio, assignors to Holophane Company, Inc., New York, N. Y., a corporation of Delaware

Application December 31, 1931, Serial No. 584,084

4 Claims. (Cl. 240—25)

The present invention relates to lighting unit and is more particularly directed toward lighting units designed for outdoor use and for illuminating objects above the level of the lighting unit at comparatively high intensity and for providing a small amount of downwardly directed light for general illumination.

Outdoor lighting such as street and yard lighting is generally designed to effect a desired light distribution on levels below the level of the lighting units employed. They are intended to light the entire area as evenly as possible consistent with the mounting height of the units, the spacing employed, and characteristics of the units used. The lighting source and light controlling means, such as refractor or reflector may, in this type of construction, be individually supported so that the proper adjustments of light source and refractor may be made to accurately focus the lamp and secure the maximum efficiency of the refractor.

The present invention contemplates a lighting unit more especially designed for outdoor use such as in lighting transmission line substations where it is desired to illuminate wires, lighting arresters, disconnecting switches, and the like which are above the lights. For more efficient use of the light and its accurate direction, a refracting unit is preferably employed about the light source.

The present invention provides a lower diffuser adapted to receive downwardly directed light which escapes below the refractor. This diffuser acts to diffuse and transmit this light downwardly for general illumination below the lighting unit.

The invention also contemplates an outdoor lighting luminair having the refractor and protective envelope so supported as to permit interior ventilation of the unit, especially between the refractor and the protective envelope.

The accompanying drawing shows, for purposes of illustrating the present invention, two of the many embodiments in which the invention may take form, it being understood that the drawing is illustrative of the invention rather than limiting the same. In the drawing:

Fig. 1 is a vertical sectional view through a lighting unit embodying the present invention with parts in section and showing in dot-and-dash lines the unit partially open;

Fig. 2 is a sectional view taken on the line 2—2 of Fig. 1 with parts broken away; and

Fig. 3 is a fragmentary view illustrating a modification.

The present form of lighting unit is provided with a suitable support, such as a tubular member 11 adapted to be tightly secured to the top of

a post or to a bracket or other device. This member is internally flanged as indicated at 12 to support a lamp socket 13. This lamp socket is adapted to carry a lamp bulb 14 with its axis vertical. The outside of the tubular member 11 is threaded as indicated at 15 to receive a casting 16.

As shown in Fig. 1, this casting has an inner ring-like portion 17 threaded to fit the member 11, an outer ring-like portion 18 of comparatively large diameter, and a number of curved ribs 19 interconnecting the two ring-like portions. At the right hand side of the drawing, the ring-like member 18 carries an upwardly extending lug 20 provided with a hinge pin 21. The opposite side of the ring-like member 18 carries a locking screw 22.

An upper ring 25 has lugs 26 mounted on hinge pin 21 and has an extension 27 to receive a threaded clamp member 22. The ring 25 has a depending rib 28 adapted to rest on the outer surface of a bead 29 provided in the ring-like member 18. The ring 25 extends inwardly as indicated at 30 to provide an annular trough 31 adapted to receive the lower edge of the outer protecting envelope 32. This envelope is secured in place by clamping screws indicated at 33.

The ring 25 has a number of inwardly extending arms indicated at 34 to support an inner ring 35, generally cast integral therewith. This inner ring is of a size to support an inverted bowl type refractor 36 of the usual type. This refractor is clamped in place by locking members 37 secured on posts 38.

The frame 16 is designed to receive a diffusing bowl 40. This may be made of crystal glass provided with diffusing corrugations, or any other form of diffusing glass and colored, if desired. This bowl is secured to the casting 16 by clamping devices indicated at 41 and packing rings 42 and 43 are employed to make a weather tight joint between the parts. The refractor 36 is adapted to concentrate the light into upward directions, such for example as indicated by the photometric curves A—A in Fig. 1. Where a two-way asymmetric refractor is used, horizontal distribution may be as indicated by the curves B—B of Fig. 2. The focusing of the lamp and the orientation of the asymmetric beams are accomplished by revolving the entire unit about the threaded support, the unit being clamped in place by a lock nut indicated at 44.

It will be noted that the refractor 36 is open at the bottom. This allows a certain part of the light to escape downwardly. It falls on to the diffuser as indicated by the light ray 45 and 110

this diffuser scatters the light as indicated, thereby providing light for illuminating the ground and surrounding objects. If the downward illumination is not desired, an opaque shield may be substituted for the diffuser or a casting 16' 5 may be designed so as to form the closed bottom of the unit optically as well as physically. This is indicated in Fig. 3.

It will be noted that the refractor is supported by the arms 34 so as to be some distance 10 inside the protective envelope and that the arrangement affords large passages 46 for air circulation inside the lamp unit. The air can pass through these openings and, owing to the large 15 exposed surface of the protective envelope, the unit can be operated with less heating of the refractor.

It is obvious that the invention may be embodied in many forms and constructions, and 20 we wish it to be understood that the particular forms shown are but two of the many forms. Various modifications and changes being possible, we do not otherwise limit ourselves in any way with respect thereto.

25 What is claimed is:

1. A luminair comprising an upright lamp bulb, a refractor open at the bottom and disposed about the lamp bulb for concentrating light into upward directions, a diffusing bowl of larger 30 outside diameter than the refractor placed below the refractor for receiving and transmitting in downward directions the direct light emitted below the refractor, a skeleton frame member to receive the diffusing bowl, a refractor supporting ring secured to the frame member and carrying the refractor, an outer protective envelope carried by the ring, and means to clamp the ring and frame member together.

2. A luminair comprising an upright lamp bulb, a refractor open at the bottom and disposed about the lamp bulb for concentrating light into upward directions, a diffusing bowl of 40 larger outside diameter than the refractor placed below the refractor for receiving and transmitting in downward directions the direct light

emitted below the refractor, a skeleton frame member to receive the bowl and having an upper ring-like portion, a ring hingedly secured to the ring-like portion of the frame member and having an inner portion and an outer portion clamped against the frame member, the inner portion supporting the refractor, and an outer protective envelope secured to the outer portion of the ring. 80

3. A luminair comprising an upright lamp bulb, a refractor open at the bottom and disposed about the lamp bulb for concentrating light into upward directions, a diffusing bowl of larger outside diameter than the refractor placed below the refractor for receiving and transmitting in downward directions the direct light emitted below the refractor, a skeleton frame member to receive the bowl and having an upper ring-like portion, a ring hingedly secured to the ring-like portion of the frame member and having an inner portion and an outer portion clamped against the frame member, the inner portion supporting the refractor, and an outer protective envelope secured to the outer portion of the ring, 85 90 95 there being large openings in the ring between the refractor and envelope to facilitate interior ventilation. 100

4. An outdoor lighting fixture comprising an upwardly opening lamp socket, a lamp bulb therein, a lamp socket support, a dish-shaped diffusing glass bowl extending upwardly and outwardly from the lamp socket, a bowl support secured to the socket support and having a ring-like portion about the upper edge of the glass bowl, a ring hingedly secured to the first ring to 105 rest on the upper face thereof, a refractor supported from said ring adjacent the lamp bulb, and an outer protective envelope carried by the ring about the refractor, there being large openings in the ring between the refractor and envelope to facilitate the flow of air currents inside 110 115 the fixture. 120
